UNITED STATES PATENT OFFICE.

HUGH JAMES DOBSON, OF NEWARK, NEW JERSEY.

SNAP-FASTENER.

1,246,069.

Specification of Letters Patent.

Patented Nov. 13, 1917.

Application filed October 31, 1916. Serial No. 128,685.

To all whom it may concern:

Be it known that I, HUGH J. DOBSON, a citizen of the United States of America, and a resident of Newark, county of Essex, in the State of New Jersey, have invented certain new and useful Improvements in Snap-Fasteners, of which the following is a specification.

The objects of this invention are to obtain a snap fastener of simplified and improved construction; to provide an improved spring for the socket member, and improved means for retaining the same in said socket member; to secure a spring which always acts with a substantially constant bowing tension; to obtain maximum freedom of action of the spring and yet hold it securely in position on the socket member; to secure great efficiency and ease of operation, and to secure other advantages and results as may be brought out in the following description.

Referring to the accompanying drawings, to which like numerals of reference indicate the same parts throughout the several views;

Figure 1 is an enlarged view of a snap fastener of my improved construction;

Fig. 2 is a section on line 2—2 of Fig. 1; Fig. 3 is a section on line 3—3 of Fig. 2;

Fig. 4 is a view of the socket member alone, looking at its side which is sewed to a garment;

Fig. 5 is a section on line 5—5 of Fig. 4; Fig. 6 is a face view of the socket member, looking at the side which is exposed in use;

Fig. 7 is a face view of the stud member, showing its side which is exposed in use;

Fig. 8 is a transverse section on line 8—8 of Fig. 7, and

Fig. 9 is a view of the stud member, looking at its side which is sewed to a garment.

In the specific embodiment of the invention illustrated in said drawings, the reference numeral 1 indicates the socket member and the reference numeral 2 indicates the stud member of my improved fastener.

The socket member, shown more particularly in Figs. 4—6, is preferably circular and of sheet metal, having a disk-like body 3 and an inwardly bent or curled flange 4 at the periphery thereof, forming a peripheral recess 5 opening toward the center of the socket member in the plane of the same. At the middle of the socket member is a central

aperture 6 through which the head 7 of the stud member 2 may be inserted from either side of the socket member, and resilient means are provided on the socket member 60 for releasably engaging said head and holding it against inadvertent withdrawal.

As shown in the drawings, the resilient holding means comprises a narrow U-shaped spring 8 arranged diametrically of the socket member, flatwise upon the side of the same from which the flange 4 projects, and having its opposite ends underlying said flange. This secures the spring against any escape from the position designated, since 70 although it might rotate with respect to the disk, if its ends are loose enough under the flange, it will always lie diametrically thereof. Preferably the open end of the U-shaped spring 8 is loose enough under the 75 said flange 4 for the arms 9, 9 of the spring to move toward each other from their normal position, which is preferably substantially parallel to each other. The normal distance between the said arms 9, 9, when 80 they are parallel, is enough less than the diameter of the head 7 of the stud member, so that when the two members of the fastener are pressed together, said head will force the arms 9, 9 apart and be frictionally held 85 therebetween by virtue of said arms closing again upon the neck 10 of the stud. Preferably, in order to increase the resiliency of the arms 9, 9 of the U-shaped spring 8, the extremities of the free ends of said arms 90 engage the bottom wall of the peripheral flange 4 to limit the separation of said ends beyond the normal position of said arms heretofore described; in this way, insertion of the head 7 to pass between the two arms 95 will bow said arms from their extremities to the closed end of the spring. This will be true no matter from which side of the socket member the stud member is inserted,

because the arms of the spring are substantially straight and held at their opposite ends. If the stud member is inserted from the opposite side of the disk-like body from the spring, obviously the arms may bow outward from the body portion somewhat as 105 they bow apart, in a direction oblique to the plane of the fastener, but the bowing will be none the less a true bowing of the arms from end to end. When the stud member is inserted from the spring side of the body, 110 of course the arms can bow only apart in the plane of the fastener, but obviously how-

ever the stud member is inserted, a bowing tension is secured, as opposed to torsional or other kinds of tensions. Of course this bowing tension is unaffected by the direction 5 or plane in which the bowing takes place, and thus by my construction I secure a substantially constant tension.

Having thus described the invention, what I claim is:

10. A snap fastener socket member, comprising a plate apertured to receive the head of a stud member from either side of itself and having its margin bent or curled over as a flange at one side of itself forming a peripheral recess open toward the center, and 15 a U-shaped spring with substantially

Copies of this patent may be obtained for five cents each, by addressing the "Commissioner of Patents, Washington, D. C."

straight arms held against the plate at its bowed end and the extremities of said arms only by said flange, said arms normally overlying opposite edges of the aperture, 20 whereby the arms of the spring always act with a substantially constant bowing tension whichever side of the socket member the stud member is inserted from.

In testimony whereof I have signed this 25 specification in the presence of two subscribing witnesses.

HUGH JAMES DOBSON.
